TAG

David Turet, New York, N. Y.

Application August 26, 1939, Serial No. 292,024

1 Claim. (Cl. 40—20)

This invention relates to tags such as price tags and the like which are adapted to be affixed to a garment by engagement with one of the buttons thereof.

5 The invention comprehends a tag having an opening therein through which a button of the garment is adapted to be passed for engagement of the tag between the button and the garment and which tag is provided with a tongue projecting outwardly from an edge thereof adjacent said opening and adapted to be folded in traversing relation with the major portion of said opening and to engage beneath the button for preventing the withdrawal of the button through said opening.

10 The invention further comprehends a tag of the indicated character in which the opening therein is located adjacent the upper edge thereof and the said tongue extends upwardly therefrom at one side of the opening and which is adapted to be folded on a line extending substantially at an angle of 45° to the plane of the projection to dispose the same in traversing relation with the lower portion of the opening and beneath the 15 button for preventing withdrawal of the button through the said opening.

15 With the foregoing and other objects in view, reference is now made to the following specification and the accompanying drawing in which there is illustrated the preferred form thereof.

20 In the drawing:

Fig. 1 is a view illustrating the tag attached to the button of a garment.

Fig. 2 is an enlarged vertical sectional view 25 taken approximately on the line 2—2 of Fig. 1.

Fig. 3 is a face view of the tag removed from the garment.

30 Referring to the drawing by characters of reference, the tag includes a body 10 of sheet material of any desired size and form which is provided with an opening 11 of a size to receive therethrough a button A of a garment so as to suspend the sheet upon the connection B which 35 joins the button to the garment.

40 As illustrated, the opening 11 is located adjacent the upper edge 12 of the tag and is of circular formation so that the same may be readily

45 passed over the button and is provided with a communicating notch 13 adjacent the upper edge of the tag for receiving therein the connection joining the button to the garment.

50 In order to prevent unintentional disengagement of the tag from the garment, the tag is provided with a tongue 14 which projects outwardly from the upper edge thereof adjacent to and at one side of the opening 11 and which has a vertical edge 15 disposed substantially parallel 55 to the vertical medial line of the opening 11. Below the tongue 14 and at one side of the opening 11 the tag is provided with a score line 16 extending across the tag from the upper edge 12 thereof to the left side edge at an angle of 45° 60 to the edge 15 of the tongue 14. The tongue 14 is adapted to be folded on the said score line from a position in which the edge 15 is parallel with the vertical medial line of the opening 11 to a position perpendicular thereto and in which position the tongue traverses the lower portion 65 of the opening 11 and is adapted to engage beneath the button A of the garment for preventing withdrawal of the button through the opening 11.

65 What is claimed is:

70 A tag for attachment to a garment including a sheet having an opening adjacent to one edge thereof and of a size to receive therethrough a button of a garment to suspend the sheet on the connection joining the button to the garment, a tongue connected to said sheet adjacent to and at one side of said opening and having an edge disposed substantially parallel with the vertical medial line of the opening, said sheet being provided with a score line at one side of said opening 75 extending substantially at an angle of 45° to the said edge of the tongue, and said tongue being foldable on said score line from a position in which the same is disposed substantially parallel to said vertical medial line of the opening to a position at right angles thereto and with the tongue disposed in traversing relation with the lower portion of the opening for engagement beneath the button of the garment for preventing withdrawal of the button through the said opening.
